UNITED STATES PATENT OFFICE

159,469

FRUIT AND VEGETABLE JUICER

John E. Bennett, San Francisco, Calif.

Application April 20, 1949, Serial No. 2,159

Term of patent 14 years

(Cl. D89—1)

To all whom it may concern:

Be it known that I, John E. Bennett, a citizen of the United States and a resident of the city and county of San Francisco, State of California, have invented a new, original, and ornamental Design for a Fruit and a Vegetable Juicer, of which the following is a specification, reference being had to the accompanying drawing, forming part hereof.

Fig. 1 is a top plan view of a fruit and vegetable juicer, showing my new design.

Fig. 2 is an elevational view of the right hand side thereof.

Fig. 3 is a front elevation thereof.

I claim:

The ornamental design for a fruit and vegetable juicer, as shown.

JOHN E. BENNETT.
